UNITED STATES PATENT OFFICE.

LLOYD N. MOWRY AND EDWARD LOVIG, OF ST. PETERSBURG, FLORIDA.

POCKET CHECK AND PASS BOOK CARRIER.

Application filed July 7, 1923. Serial No. 650,065.

To all whom it may concern:

Be it known that we, LLOYD N. MOWRY and EDWARD LOVIG, citizens of the United States, residing at St. Petersburg, in the county of Pinellas and State of Florida, have invented certain new and useful Improvements in Pocket Check and Pass Book Carriers, of which the following is a specification.

10 In carrying out the present invention, it is our purpose to provide a highly novel and useful form of carrier for check and pass books wherein the same may be carried together in a compact manner by bank depositors, etc.

15 The primary object of the invention resides in the provision of such a carrier, wherein novel means is provided for the carrying of the check book for permitting the same to be fully extended for providing a support for the checks during the writing of the same.

20 A still further object is to provide such a carrier wherein means is provided for scarifying the check after the same has been written for thereby lessening the liability of the checks being raised.

25 Yet another object is to provide such an article that is so simple of construction and inexpensive of manufacture that the same may be given away by banking institutions and the like for advertising purposes.

30 The nature and advantages of the invention will be better understood when the following detailed description is read in connection with the accompanying drawing, the invention residing in the construction, combination, and arrangement of parts as claimed.

35 In the drawing forming part of this application, like numerals of reference indicate similar parts in the several views, and wherein:

40 Figure 1 is a perspective view of our novel check and pass book carrier, the movable walls of the same being shown as extended, and

45 Figure 2 is a similar view of the carrier in its closed condition.

50 Figure 3 is a fragmentary cross section of the casing taken upon the line 3-3 of Figure 1, and

55 Figure 4 is an enlarged cross section of the check scarifying means, that forms an essential part of the present invention.

Having particular reference to the draw-

ing, our novel carrier embodies a small flat-like rectangular shaped receptacle 5 of any desirable material and open at one end. Within this receptacle is a partition wall 6 spaced a slight distance away from the top wall of the receptacle for according a compartment 7 for the reception of a pass book. However, in the future practice of the invention, this receptacle may be made without such a compartment, in this instance, it being only necessary to make minor changes in the other parts of the device.

60 The outer end of this partition 6 is notched at 8, whereby the pass book may be readily withdrawn from the said compartment.

65 Adjacent one side of the receptacle 5, the end walls thereof are provided interiorly with aligned longitudinal channels 9, the opposite ends of which terminate slightly inwardly of the opposite ends of the receptacle. Projecting into these channels 9 and freely movable therein are right angularly extending pins 10 formed upon the inner end of a plate 11, the length of which is slightly lesser than the length of the receptacle. Hingedly connected to the free end of said plate 11 and flush therewith when the device is extended, is a narrow plate insert 12, to which is also hingedly secured at the opposite edge thereof, the inner end of a plate 13 of dimensions substantially similar to those of the before mentioned plate 11.

70 Upon the outer edge of the plate 13 is an inwardly directed open sided housing 14 of slightly lesser length than the width of the plate, the top and bottom walls of which are slotted adjacent their outer ends at 15. Within this housing 14, and at its inner side is a vertical roller 16, the opposite ends thereof carrying pintles for projection through openings in the top and bottom walls of the housing, said roller being formed of suitable material for cooperation with a milled roller for scarifying a check. 75 Freely movable within the slots 15 of the housing are pintles carried by the opposite ends of a milled roller 17, the length of these pintles being such as to project through the slots 15 and engage within openings of the top and bottom walls of an elongated U bracket 25. As more clearly shown in Figure 4, the top and bottom walls of this bracket engage over the similar walls of the housing 14, and are slidably

secured thereto by relatively long rivets 26 that engage through the slots 15 of the housing 14.

As a means for maintaining this bracket 25 in the outwardly extended position shown in Figure 4, as well as maintaining the milled roller 17 in slightly spaced relation to the roller 16, a spring 27 is provided between the outer side of the housing 14 and the inner 10 side of the vertical portion of said bracket 25, this spring 27 being secured to the bracket, through the medium of a rivet 28.

The plate insert 12 is formed at its opposite ends with inwardly directed ears 18, the 15 edges of which are curved as shown and are adapted for projection into notches 19 upon the ends of the side walls of the receptacle 5 when the plates 11 and 13 are folded upon each and moved into the receptacle.

20 In actual practice, a check book is to be engaged at its bound end within a pocket 20 carried by the inner face of the plate 11, the check book being then extended upon the plates 11 and 13, and passed beneath 25 inwardly directed pins 21 carried by the said ears 18 of the plate insert 12. The outer end of this check book terminates at a point slightly distant from the roller carrying housing 14, and after the check book has 30 been properly positioned upon the plates 11 and 13, the same may be folded and moved into the receptacle, it being noted in this connection that the end walls of the receptacle are provided internally with additional 35 channels 22 at the inner side of the partition wall 6, the front ends thereof terminating at the open end of the receptacle for receiving the opposite edges of the plate 13.

40 For fully closing the open end of the receptacle 5, the plate insert 12 is formed with an offset flange 23, that extends parallel with said plate insert, and is adapted for overlying the end of the compartment 7 when the 45 plates 11 and 13 are properly positioned within the receptacle in a manner clearly shown in Figure 2. It is obvious however, that should this receptacle 5 be manufactured without the said compartment 7, this 50 offset plate 23 will not be necessary.

It will be apparent that when the plates 12 and 13 are extended to the position shown in Figure 1, and when a check book is supported thereby, any number of the same may 55 be filled in. When one of the checks have been filled in, it is torn from the book and positioned at its outer end between the

rollers 16 and 17. A pressure upon the U-bracket 25 will move the milled roller 17 in close proximity to the roller 16 whereby a 60 further movement of the check between the rollers will effectively scarify the same for purposes above set forth.

From the foregoing, it will be obvious 65 that we have provided a highly useful form of novelty that may be given away by banking institutions whereby the pass and check books of its depositors may be carried thereby in a compact manner, and even though we have herein shown and described the preferred embodiment of the present invention, 70 it is nevertheless to be understood that minor changes may be made therein, without departing from the spirit and scope of the invention as claimed.

Having thus described our invention, what we claim as new, and desire to secure by Letters Patent, is:

1. In a carrier for pass and check books, 80 an open ended receptacle, a pair of separated and hingedly joined plates mounted for free sliding movement within the receptacle, and means carried by said plates for supporting a check book in either opened or closed position.

2. In a carrier for pass and check books, 85 a receptacle, a plate member mounted for sliding movement within said receptacle, another plate member separated from and hingedly secured to said first mentioned plate member and having free sliding movement within the receptacle when folded to a position parallel with said first mentioned plate member, and means carried by said plate members for supporting a check book. 90

3. In a carrier for pass and check books, a receptacle, a plate member mounted for sliding movement within said receptacle, another plate member separated from and hingedly secured to said first mentioned plate member and also mounted for free sliding movement within the receptacle when folded to a position parallel with said first mentioned plate member, and means carried by said plate members for supporting a check book, the hinged connection between said plate members affording a closure for the open end of the receptacle when said plate members are folded and extended within the receptacle. 100

In testimony whereof we affix our signatures.

LLOYD N. MOWRY.
EDWARD LOVIG.
